[57] CLAIM

The ornamental design for a "work light fixture", as shown and described.

DESCRIPTION

FIG. 1 is a perspective view of the invention showing our new design;

FIG. 2 is a front elevation view thereof;

FIG. 3 is a right elevation view thereof;

FIG. 4 is a back elevation view thereof;

FIG. 5 is a left elevation view thereof;

FIG. 6 is a top plan view thereof;

FIG. 7 is a bottom plan view thereof.

The surface pattern shown on the interior surface behind the transparent lens, is partially shown for convenience of illustration, it be understood that the pattern is uniformly continuous over said surface.
